CLAIM

The ornamental design for a safety cutter, as shown and described.

DESCRIPTION

FIG. 1 is a top plan view of the safety cutter showing my new design;

FIG. 2 is a bottom plan view thereof;

FIG. 3 is a left side elevational view thereof;

FIG. 4 is a right side elevational view thereof, mirroring the left side elevational view;

FIG. 5 is a first top perspective view thereof;

FIG. 6 is a first bottom perspective view thereof;

FIG. 7 is a second bottom perspective view thereof;

FIG. 8 is a second top perspective view thereof;

FIG. 9 is a further perspective view thereof;

FIG. 10 is a further perspective view thereof;

FIG. 11 is a front, or head-end, elevational view thereof;

FIG. 12 is a rear, or tail-end, elevational view thereof;

FIG. 13 is a further perspective view thereof;

FIG. 14 is a further perspective view thereof;

FIG. 15 is a further perspective view thereof; and,

FIG. 16 is a further perspective view thereof.
